UNITED STATES PATENT OFFICE.

JONATHAN LEE KNIGHT, OF KANSAS CITY, MISSOURI, ASSIGNOR TO A. U. MORSE, OF KANSAS CITY, MISSOURI.

HAND-OPERATING EYELETING-MACHINE.

No. 900,935.

Specification of Letters Patent.

Patented Oct. 13, 1908.

Application filed July 21, 1905. Serial No. 270,676.

To all whom it may concern:

Be it known that I, JONATHAN LEE KNIGHT, a citizen of the United States, residing at Kansas City, in the county of Jackson and State 5 of Missouri, have invented certain new and useful Improvements in Hand-Operated Eyeletting-Machines, of which the following is a specification.

This invention relates to parallel-jaw 10 punching and eyeletting tools, and has for its object to produce a device of this character by which holes and eyelets of different sizes may respectively be punched and set.

A further object is to produce a device of 15 this character of simple, strong, durable and cheap construction.

With these objects in view the invention consists in certain novel and peculiar features 20 of construction and organization as hereinabove described and claimed; and in order that it may be fully understood reference is to be had to the accompanying drawing, in which—

Figure 1, is a view partly in side elevation and partly in central longitudinal section, the 25 tool being open. Fig. 2, is an edge view with the tool closed. Fig. 3, is a section on the line X—X of Fig. 1. Fig. 4, is a section on the line Y—Y of Fig. 1. Fig. 5, is a plan view of the head end of one of the handles. 30 Fig. 6, is a detail side view of the punch.

In the said drawings, A indicates a pair of levers formed preferably of sheet metal, provided with what are usually known as hollow handles and bifurcated heads, said heads extending inwardly and forwardly at an angle to the handles with the bifurcations in the plane of the grooves of the latter.

Each head is provided at the rear end of the inner edge of one of its branches or arms 40 with an offset A' projecting inwardly of the corresponding edge of the companion branch or arm. The heads are also provided forward and outward of said offsets with holes 2 through which a pivot 1 extends to connect 45 the levers together, it being noted by reference to Fig. 4, particularly, that the offsets A' of the handles are disposed at opposite sides of the pivot from each other and by reference to said figure and Figs. 2 and 3, that the 50 arms or branches equipped with said offsets are fitted against the inner sides of the other arms or branches of the lever.

B indicates a pair of similar parallel jaws arranged at opposite sides of pivot 1, each having 55 its rear end projecting into the hollow por-

tion of one of the handles and its front end fitting in the bifurcated head of the other handle and pivotally connected to the latter by a pivot pin 3, said pins extending parallel with pivot 1 and engaging holes 4' in the said heads. The rear ends of the jaws B terminate in flat lugs B³ disposed opposite each other in the plane of the longitudinal center of the handles. F indicates parallel links extending transversely of the jaws at the outer sides 60 of the flat lugs B³ thereof, each link being pivoted at one end by a pin 5 to a different lug B³ and at the opposite end to a pin 7 projecting inwardly from the offset A' of the handle to the head of which the companion jaw is 65 pivoted, the arrangement being such that the links are spaced apart a distance substantially corresponding to the thickness of the lugs B³.

In the construction thus far described the 75 movement of the lever handles toward each other results in a movement of the jaws toward each other in parallel relation, a coil spring E between the arms or branches of the heads and between the links F and pivot 2 80 resisting the movement described and serving to impart opposite or opening movement to the tool.

Each jaw is provided in transverse alignment and forward of the pivot 2 with a guide 85 passage 4 and is also equipped at its outer side with an arm B', said arm curving outward and forward from the jaw contiguous to flat lugs B³ and extending forward to a point beyond the contiguous guide passage 90 4 to provide a mouth 6, for a purpose herein-after explained, the arms B' having passages 8 alined with passages 4 and forming female dies to coöperate with the male dies or punches C, C, which as shown clearly in Fig. 95 6 are preferably of different diameter so as to punch holes of different sizes, it being understood of course that the female dies are likewise of variable size as shown in Figs. 1 and 2.

The dual punch above described is provided with a rigid stem C' which extends rearwardly through the pivot 1, which thus acts to prevent endwise movement of the punch, lateral movement being prevented because 105 the latter is continuously engaged with guide passages 4.

B² indicate tenons projecting forward from the front end of the jaws, and rotatably adjustable thereon are eyeletting blocks D, set 110

- 2
- screws D' being mounted in blocks D to engage the tenons and clamp said dies in the desired relation, that is with the male die 9' of one facing the female die 10 of the other.
- 5 It is preferred that each block shall be equipped with a male and female die and that such dies shall be of different diameters so as to accommodate the different sized holes produced by the dual punch.
- 10 In practice paper, leather or other material is slipped into the proper mouth 6, and the handles brought together to punch a hole in such material. A rivet may then be inserted in the material and placed between
- 15 the correspondingly sized dies 9' and 10, the levers being again operated to set the rivet. In the movement of the handles toward each other, the links move oppositely endwise until each laps lug B³ at the opposite side
- 20 from the link pivotally attached to each lug, and to accommodate this movement of the links said lugs are disposed centrally of the jaws B as hereinbefore stated.

In Fig. 4, the tool is open and for this reason the flat lugs B³ of the jaws are disposed outward of the contiguous end of the link carried by the lug of the companion jaw, and it will be readily seen by reference to Fig. 4 that when the jaws are caused to approach

30 the upper link F will pass above the right hand lug B³ and the lower link below the left-hand lug B³.

From the above description it will be apparent that I have produced a tool possessing the features of advantage enumerated as desirable and I wish it to be understood that I do not desire to be limited to the exact details of construction shown and described as obvious modifications will suggest themselves

40 to one skilled in the art.

Having thus described the invention what I claim as new and desire to secure by Letters Patent, is:—

1. A tool of the character described, comprising a pair of crossed levers consisting of handle and bifurcated head portions, and each provided with a lug projecting inwardly from its handle portion, a pivot connecting said levers at their crossing points through
- 45 said head portions, a pair of longitudinal jaws at opposite sides of the pivot with their front portions fitting in the bifurcated heads of different levers and their rear ends projecting into the hollow handles of the other levers
- 50 and provided centrally at such ends with flat lugs, a link pivotally connecting the flat lug of one of said jaws with the inwardly projecting lug of the lever in the bifurcated head of which the other jaw is pivoted, a similar
- 55 link pivotally connecting the flat lug of the

other jaw with the flat lug of the other handle, and a spring for holding said jaws yieldingly apart.

2. A tool of the character described, comprising a pair of crossed levers consisting of handle and bifurcated head portions, and each provided with a lug projecting inwardly from its handle portion, a pivot connecting said levers at their crossing points through

65 said head portions, a pair of longitudinal jaws at opposite sides of the pivot with their front portions fitting in the bifurcated heads of different levers and their rear ends projecting into the hollow handles of the other levers and provided centrally at such ends

70 with flat lugs, a link pivotally connecting the flat lug of one of said jaws with the inwardly projecting lug of the lever in the bifurcated head of which the other jaw is pivoted, a similar link pivotally connecting the flat lug

75 of the other jaw with the flat lug of the other handle, and a spring pressing outwardly against said jaws and arranged between the pivot of the levers and said links and prevented by said pivot and links from slipping

80 out of operative position.

3. A tool of the character described, comprising a pair of crossed levers, consisting of handle and bifurcated head portions, a pivot connecting said levers at their crossing points

85 through said head portions, a pair of longitudinal jaws at opposite sides of the pivot, each with its rear end projecting into the bifurcation of one of the levers and its front end fitting in the front end of the bifurcation

90 of the other lever, one jaw having a transverse passage forward of the pivot, an arm rigid with and outward of the jaw provided with a passage and provided with an aligned

95 passage or female die, pivots extending

100 through the jaws at the front ends of the levers, flat lugs at the rear ends of the jaws, a pair of transversely extending parallel and overlapping links occupying the bifurcations of the levers and each pivoted at

105 one end to one of said levers and at its opposite end to the flat lug of the jaw pivoted to the other lever, said links being disposed at the outer sides of the lugs, a transverse punch or male die fitting in the passage of

110 said jaw, and a stem rigid with the punch and extending rearwardly through and carried by the pivot of the levers.

In testimony whereof I affix my signature, in the presence of two witnesses.

JONATHAN LEE KNIGHT.
